TOY ANIMATION PICTURE DEVICE

Kurt Juhn, New York, N. Y.

Application January 5, 1945, Serial No. 571,507

6 Claims. (Cl. 88—19)

1

The invention relates to improvements in toy animation picture devices in which pictures successively presented are designed to be viewed through a sight aperture element upon rotation before the same of a carrier for the pictures.

An object of the invention is to provide a novel picture bearing strip or band for use in a device of this nature, and which band may be readily replaceable therein.

Another object of the invention is to provide a novel form of picture band whereby it is possible to exhibit two different series of pictures from a single band merely by reversing the direction of the band movement and viewing the different series of pictures respectively through different apertures of the sight aperture element which are brought into position by turning over the device through 180°.

The invention has for an object, also, to provide an animation picture device which can be sold in knock-down and unassembled condition in a flat package, suitable for mailing, and a device which is inexpensive and simple to manufacture.

A further object of the invention is to provide a picture animation device which may be readily assembled from elements cut or broken out of flat stock; and, when assembled, is simple in operation to afford the desired entertainment.

In carrying out the invention, the novel device comprises a suitable frame affording an abutment or retarder portion for engaging the free ends of picture elements mounted on a strip or band which is adapted to be detachably secured over the periphery of a rotor rotatably supported in the frame to rotate about an axis substantially parallel to the said retarder portion of the frame. The said frame is provided, also, with a lateral extension whereby the device as a whole may be manually supported, and the rotor element is mounted upon an axle to be rotated manually by a suitable crank handle.

If desired, the various elements of the device may be cut or broken out of a flat sheet of suitable material such as cardboard, strawboard or the like, said elements being formed in a blank of material by perforated outlines. In assembling the elements, they are secured as by gluing portions together and by means of interlocking members, all without requiring particular mechanical skill.

The picture bearing elements to be exhibited are not carried directly by the rotor of the device but upon a flexible band or strip which may be detachably secured to the rotor over its periphery

2

with the individual picture elements secured to a surface of the band in a manner such as to extend in a generally radial direction outwardly when the band is applied to the rotor. A picture element is designed to receive pictures on both faces such that two different showings may be had with a single band merely by rotating the band in opposite directions and viewing respectively the successions of pictures through different windows or apertures of a sight aperture element screening in part the frame and rotor.

The nature of the invention, however, will best be understood when described in connection with the accompanying drawings, in which:

15 Fig. 1 is a view of a blank perforated to outline the various elements of which the novel device may be constructed, when the same is to be provided in a knock-down condition.

Fig. 2 is a plan view, partly in horizontal section, of the novel device as assembled from the elements included in Fig. 1, and with a picture strip located on the rotor of the device.

Fig. 3 is an elevation of the operating end of the device.

25 Fig. 4 is a front elevation of the device; and Fig. 5 is a transverse section therethrough, taken on the line 5—5, Fig. 4 of the drawings, looking in the direction of the arrows.

Fig. 6 is a plan view of the novel picture strip 30 with a number of the picture bearing elements positioned thereon; and Fig. 7 is a longitudinal section thereof, taken on the line 7—7, Fig. 6 of the drawings.

Fig. 8 is a plan view of a modified form of the 35 picture strip with a number of the picture elements positioned thereon; and Fig. 9 is a longitudinal section thereof, taken on the line 9—9, Fig. 8 of the drawings.

Fig. 10 is a fragmentary plan view of a blank 40 printed and perforated to provide the individual picture bearing elements for two different sequences of picture showings.

Referring to the drawings, more particularly 45 Figs. 2 to 5 thereof, a more or less rectangularly shaped frame member comprises the bearing ends 20 and 21, respectively, with an extension 22 from the former, and an intermediate abutment or retarder portion 23 for engaging the free end of a picture element as the same is moved or rotated thereover, as hereinafter more fully set forth. The said retarder portion is also extended from its outer face in opposite directions to provide a sight aperture portion 24 lying in a plane substantially at right angles to the plane of the frame. This aperture portion is provided prefer-

ably with two sight apertures 25 and 26, which may be provided with magnifying lenses (not shown) if desired. These apertures are positioned respectively on opposite sides of the retarder portion 23 and are aligned with the travelling picture elements 27 for viewing of a picture through one or the other of the apertures, as indicated in Fig. 4 of the drawings. Each of the picture elements is retained by a strip or band 28 supported on the periphery of a rotor 29.

Rotor 29 is designed to be mounted, for example, upon a square shaft or axle 30 journaled in the frame ends 20 and 21, or rather in the specific embodiment of the invention shown, in an extension portion 31 of the end 21. The axle 30 is continued outwardly beyond the frame or extension 31 to receive a crank 32 with operating handle 33 whereby the rotor may be turned in the desired direction, it being understood that the device as a whole is manually retained by the supporting extension 22.

While the device hereinbefore described may be constructed for delivery completely assembled and of finished and substantial elements, it may be desirable to provide the same in knock down condition for assembly after shipment, and the specific form of the device shown in the drawings has been designed with this end in view. Thus, all of the elements required may be derived from a flat sheet or blank 40, Fig. 1 of the drawings; and the picture bearing elements may also be assembled on the strip at the point of use, or the completed strip with picture elements applied may be separately provided, as desired.

As indicated in Fig. 1, the sheet 40 has outlined thereon, by means of perforations, substantially all of the elements required to assemble the animation picture device hereinbefore described, these elements being cut or broken out along the perforated outlines, as is well understood. The one surface of the sheet is coated over with a suitable adhesive so that the particular elements requiring securing may be conveniently constructed from the different parts by matching the contacting surfaces and attaching the same to each other by moistening the covered surfaces. For example, the frame member may be constructed by the two like cut-outs 41 designed to be secured to each other through the adhesive surfaces. The wing portion 24, which is provided with a knock-out portion for an aperture 25 or 26, is scored along the line 42 to permit of bending the same outwardly, said wing portion of one cut-out 41 being bent in a direction opposite to that in which the other is bent with respect to the frame; and these bent portions are preferably reinforced by an additional sight aperture portion as the cut-out 24' having knock-out portions for apertures 25' and 26' designed to register with the corresponding apertures 25 and 26 of the wing portions 24. This reinforcing portion is secured over the outer surfaces of the wings 24 through the adhesive coating, and the extension portion 31 of the end 21 of the frame is also included with the cut-out 24' and is bendable at right angles thereto along the scoring line 43 to be secured to said end through the adhesive coating. A circular knock-out portion in the extension provides a bearing 44 for the axle 30.

To construct this axle, the same may be constituted of a plurality of plies in the nature of elongated cut-outs 45, outlined as indicated, two cooperating plies being slit inwardly at one end to receive a journal 46 for mounting the axle in the one end 20 of the frame. Such journal 46

is held in place from lateral displacement by a pair of paper or cardboard retaining plates 46'. The crank 32 may be provided of a pair of cut-outs 47 which are to be superposed and united, and have square knock-outs to provide registering apertures 48 of dimensions similar to those of the axle for mounting of the crank thereon. Small circular knock-outs 49 are also provided to afford registering openings in the outer end 10 of the crank designed to receive the handle 33. Both the handle 33 and the journal 46 may be removably attached to the sheet 40 by means of the adhesive thereover so that said sheet may provide all of the necessary elements for constructing the novel device.

The rotor element of this device may conveniently be constructed therefrom in providing a plurality of disks which may similarly be cut out and assembled as hereinafter set forth. Thus, two circular end disks 50 are outlined and each is provided with a square central knock-out to afford an opening 51 through which the axle 30 may pass and secure said disks 50 thereon against relative rotation. Provision is similarly made for 20 a pair of diametrically disposed slots 52 within the circumferential outline, as well as a pair of diametrically disposed inwardly directed slits 53 at right angles to said slots. In addition, provision is made for a holding, radially-disposed slit 54 and a further holding but curved slit 55 which are circumferentially displaced from each other and are directed inwardly from the circular outline.

Between the said end disks 50 there is designed to be mounted upon the shaft 30 a plurality of circular disks 60 which are outlined by the perforations and are provided with a central circular knock-out to afford an opening 61 designed to pass the axle, with diametral slits 62 extending 30 radially therefrom. Provision is made, also, for a pair of diametrically disposed slits 63 inwardly directed from the circumference of said disks 60 and at right angles to the slits 62.

Means are provided to interlock the disks 60 with the end disks 50 on said axle so that all may rotate with the latter. This may conveniently be effected by pairs of spacing elements 65 and 66 which are outlined as indicated, Fig. 1. Both pairs are further outlined to provide slits 67 and 68, respectively, directed inwardly from a longitudinal edge thereof. In addition, the spacing elements 66 are outlined to provide reduced ends or tabs 69. To assemble the various disks, the slits 62 of the lesser diameter disks 60 are aligned 55 to receive spacing elements 66 which are introduced through the openings 61, and the slits 68 of a spacing element are brought to interlock with corresponding slits 62 of the disks 60. The end disks 50 are then mounted on the axle with their slots 52 fitted over the respective ends 69 of spacing elements 66. This secures alignment of slits 53 of the end disks with the slits 63 of the intermediate disks; and spacing elements 65 are then inserted into said slits with the corresponding slits 67 interlocking therewith. This affords a sufficiently rigid rotor element designed to receive over the periphery of the intermediate disks and between the end disks, which afford end guides, the picture bearing strip or band 28.

70 This band with picture elements carried thereby is shown more particularly in Figs. 6-10 of the drawings. As indicated therein, the band 28 is of sufficient length to allow of being wrapped entirely over the periphery of the rotor as well 75 as to allow of a slight overlap conforming to the

displacement of the holding slits 54 and 55. The band is preferably of substantial thickness but is rendered sufficiently flexible for the purpose, for example, by transverse scoring lines 70, provided over the surface, except at the ends of the band. These ends are maintained relatively rigid and for this purpose may be doubled upon themselves, as indicated in Figs. 8 and 9 of the drawings. These ends are also provided with lateral extension 71 and 72 for fitting respectively the slits 54 and 55.

Band 28 is also transversely slotted along the said scoring lines which are uniformly spaced, the slotting being designed to provide openings 75 for mounting picture elements 76. These picture elements are formed of a more or less flexible strip which is doubled upon itself at regular intervals to provide a succession of picture elements extending longitudinally along the band to project outwardly from its surface at each of the openings or slots 75 with outer faces more or less convex. By providing a picture element as a doubled portion of the picture bearing strip, pictures may be provided on both exposed faces of the element for animation of two different sequences, as will hereinafter be more fully set forth.

The picture bearing strip is conveniently attached to the band 28 by threading the same through the transverse openings 75 therein and by having the under surface of the band 28 coated with a suitable adhesive which, when moistened, allows of the attachment particularly at the ends of the bearing strip of tab portions 77 at the respective ends. Or, as indicated in Figs. 8 and 9, the upper surface of band 80 may be coated with an adhesive 81 and the end tab portions 82 as well as the clear portions 83 of the picture bearing strip 84 secured directly to this upper surface of the band.

The said picture bearing strip may be provided in any convenient manner, and one means of affording such strip is indicated in Fig. 10 of the drawings. For example, a sheet 85 may be perforated longitudinally to provide a series of adjacent rows of narrow picture strips 86 of pairs of picture frames, the pictures of a pair being of differing sequences, and the strips affording a series of separate sections of pictures for convenience in attaching a strip to its carrying band. The pairs are consecutively numbered to assure correct mounting of a strip upon its carrying band 28, and a fold line 87 separates the two different pictures of a pair. The strip is intended to be doubled upon itself at each of these fold lines to present a single double-faced picture element with the intermediate and narrow blank tab portions 88 between pairs of pictures for attachment.

Operation of the device will be apparent from Figs. 3-5, inclusive, it being necessary merely to wind the picture bearing band, with double-faced picture elements projecting therefrom, about the periphery of the rotor member, as shown in Fig. 3. The device is then supported in the position indicated in Fig. 4, with one hand of the operator grasping the extension 22 and the other operating the crank handle 33 to rotate the axle 30 in a clockwise direction. As the rotor is turned in this direction, the picture elements contact at their respective outer ends with the abutment or retarder member 23, a picture element being released from contact therewith to snap suddenly up into a more or less vertical position wherein it is visible through the sight aperture 25. By

5 regulating the angular velocity of the rotor member, there may be produced a sequence of action or animated effect from the successively presented pictures. To secure presentation of the other sequence of pictures, it is necessary merely to reverse the device and hold the extension 22 in position with the other or right hand and effect with the left hand rotation of the rotor in a clockwise direction. This brings into position for 10 viewing the pictures through the other sight aperture 26.

It will be understood that the same result may be obtained without inverting the device merely by imparting a counterclockwise rotation to the rotor, in which case, however, the arrangement of the pairs of individual pictures on the doubled portions of the strip is such that these pictures all face in the same direction.

I claim:

20 1. An exhibiting device, comprising a frame affording a single retarder portion, a rotor supported therein to rotate about an axis substantially parallel to said retarder portion, together with means whereby to rotate the rotor, and a flexible picture-bearing band detachably wrapped over the periphery of the rotor for rotation therewith, together with flexible picture elements having pictures on their opposite faces, said elements being adapted to project outwardly from the band and rotor in a generally radial direction and designed to contact successively at their free ends with the said retarder portion as the rotor is rotated in either direction, and a sight aperture element screening in part the frame and rotor and affording a pair of apertures located respectively at opposite sides of the retarder portion for viewing respectively pictures upon opposite sides of the picture elements following contact of a picture element with the retarder portion and in accordance with the direction of rotation of the said rotor.

25 2. An exhibiting device, comprising a rectangularly shaped frame with bearing ends and an intermediate single retarder portion, there being provided at one end of the frame an extension for supporting the device, and said retarder portion being extended at right angles to the plane of the frame and provided with a pair of sight apertures located at opposite sides of the retarder portion, a rotor element mounted between the ends of the frame for rotation about an axis substantially parallel to the said retarder portion, together with means external the frame for rotating said rotor, and a flexible picture-bearing band removably supported over the periphery of the rotor for rotation therewith, together with flexible picture elements having pictures on their opposite faces, said elements projecting outwardly from the band and rotor in a generally radial direction and contacting successively at their free ends with the said retarder portion as the rotor is rotated in either direction for viewing through the corresponding sight aperture respectively pictures following contact with the retarder portion in accordance with the direction of rotation of said rotor.

30 3. An exhibiting device as claimed in claim 1, in which the rotor is carried upon a shaft mounted for rotation in the ends of the frame and comprises a pair of end disks and intermediate disks of lesser diameter, together with means to hold the disks together in spaced relationship, the picture-bearing band being designed to fit over the intermediate disks between

the end disks and to be removably attachable to the latter disks.

4. An exhibiting device as claimed in claim 2, in which the frame, with end extension, intermediate retarder portion and sight aperture portions, is constructed of a pair of duplicate pieces secured together, and a reinforcing plate is secured over the sight aperture portions with apertures thereof registering with the apertures of said sight aperture portions, and is bent at right angles and secured to one end of the frame to afford a bearing for the rotor, the opposite bearing being provided by the inner portion of the said end extension.

5. A rotor assembly for mounting upon a square-section axle, comprising a pair of spaced-apart end disks with square central openings to fit the axle for rotation therewith, a pair of diametrically disposed slits in each of the disks directed inwardly from the circumference thereof and a pair of diametrically disposed slits in each of the disks at right angles to the said slits thereof, each of said disks also being provided with a radial holding slit and a circumferentially displaced curved holding slit both directed inwardly from the circumference; a plurality of intermediate disks having central circular openings, said disks being of lesser diameter than the said end disks, and each having a pair of diametrically disposed slits at right angles to the said circumferential slits and extending inwardly from the respective central circular openings thereof; and longitudinal strips inwardly slotted to align circumferential slits of the respective end disks and retain the latter in spaced relationship, and additional longitudinal strips inwardly slotted to fit the slits from the circular openings of the intermediate disks and having end tabs fitting through the slots of the respective end disks.

6. An exhibiting device, comprising an element including a frame of a pair of duplicate pieces secured together into a flat, rectangularly shaped member with ends and an intermediate retarder portion, there being provided at one end an ex-

5 tension affording means for supporting the device, the opposite end being of reduced length and the retarder portion having oppositely directed extensions at right angles to the plane of said frame provided with respective sight apertures, a rotor mounted between the ends of the frame for rotation about an axis substantially parallel to the said retarder portion, together with means external the frame for rotating manually said rotor, which includes end disks and intermediate disks of lesser diameter, together with means to attach the latter disks to the former disks in spaced relationship; and a flexible picture-bearing band removably supported on the periphery of the rotor, for rotation therewith, and attached thereto through slits of the end disks inwardly directed from the circumference thereof, together with flexible picture elements projecting outwardly from said band and rotor in a generally radial direction and designed to contact successively at their free ends with the said retarder portion as the rotor is rotated for viewing a picture through a sight aperture.
